UNITED STATES PATENT OFFICE.

VERNON ROYLE, OF PATERSON, NEW JERSEY.

ATTACHMENT FOR ROUTING-MACHINES.

1,353,497.

Specification of Letters Patent. Patented Sept. 21, 1920.

Application filed December 13, 1916. Serial No. 136,706.

To all whom it may concern:

Be it known that I, VERNON ROYLE, a citizen of the United States, and resident of Paterson, in the county of Passaic and State of New Jersey, have invented a new and useful Improvement in Attachments for Routing-Machines, of which the following is a specification.

This invention relates to an improvement in attachments for routing machines, with the object in view of providing a simple and effective device for locking the cutter supporting bar to the guide rail of routing machines, designed to be used more particularly in conjunction with an ellipsograph attachment, whereby a series of concentric, elliptical cuts may be made with a routing cutter in each of a series of plates (e. g. photoengraving plates); presented to the cutter, without resetting the device.

Another object is to provide a device which will, when locked to the guide rail, allow the cutter supporting bar a limited radial adjustment, whereby the space between the cuts may be varied.

A further object is to provide certain improvements in the form, construction, and arrangement of the several parts of the device whereby the above-named and other results may be effectively attained.

In practice, when a finished photo engraving plate is printed, the inner cut presents a white border line, while the intervening strip between the cuts presents a black border line concentric with the white border line.

A practical embodiment of my invention is represented in the accompanying drawings, in which

Figure 1 represents a side elevation of the upper portion of a routing machine with my improved device applied thereto, and showing an ellipsograph attachment secured in position on the routing machine.

Fig. 2 represents a detail plan view, on an enlarged scale, of the device applied to the guide rail and holding the cutter supporting bar in one position.

Fig. 3 represents a plan view of the same showing the cutter supporting bar held in another position.

Fig. 4 represents a front elevation of the same,

Fig. 5 represents a side elevation of the same,

Fig. 6 represents a detail vertical section

taken through one of the means for locking the device to the guide rail,

Fig. 7 represents a plan view of a portion of an engraved plate showing the cuts 60 made with the routing cutters of different diameters, and

Fig. 8 represents a vertical section taken in the plane of the line VIII—VIII of Fig. 7.

The portion of the routing machine herein shown is of well known and approved construction, disclosed, for example, in Letters Patent No. 442826, dated December 16, 1890, and in a copending application 70 Serial No. 726069, filed October 16, 1912, in which I am one of the joint applicants.

The bed plate of the routing machine is denoted by 1; the pedestal on which it is mounted, by 2; the cutter supporting bar 75 by 3; the cutter holder by 4, and the cutter by 5. These parts may be of any well known or approved form and suitable well known means may be employed for driving and manipulating the cutter holder.

An ellipsograph attachment, having a base frame 6, is intended to be removably attached to the bed plate 1 between an adjustable clamp 7 and an abutment 8 carried by the bed plate. The clamp 7 is arranged 85 to be moved longitudinally in suitable grooves 9 and locked in various adjustments by means of a T-bolt 10, the head of which fits in the groove 9 and the stem of which extends upwardly through the clamp 7 in 90 position to receive a hand wheel 11 for locking the clamp to the bed plate.

The abutment 8 is arranged to be held in various positions by means of a pin 12 depending therefrom, which is adapted to 95 enter holes 13 in the bottom of the groove 9.

The base frame 6 of the ellipsograph attachment has a tool holder 14, carrying a turret head 15 rotatively mounted on a stud 16 screwed into the holder. The turret head 100 15 is provided with a lining tool 17, and a series of sockets 18 into which other tools may be placed.

The table 19, for supporting the plate 20 to be cut, is mounted to rotate on the base 105 frame 6 and provided with clamps 21 which hold the plate in position to be cut by the cutter 5 or engraved by the lining tool 17. The table is also provided with a series of handles 22 for conveniently rotating it on 110 the base frame 6. A guide rail 23, which forms a rest for the cutter supporting bar 3

or for the arm of the operator or for both, in manipulating the cutter 5, is fixed to supporting heads 24 which are carried by the upper ends of guide rods 25 mounted to slide in standards 26 on the bed plate 1. The rods 25 have a free vertical sliding movement within the standards and thus the guide rail 23 may be elevated and depressed.

- To the lower end of each rod, one end of 10 an operating lever 27 is coupled, the opposite end of said lever being connected with a foot pedal (not shown) by a connecting rod 28. The operating lever 27 is fulcrumed upon a swinging link 29 attached to the bed plate 1, which link compensates for the tendency of the end of the lever 27 to travel out of the line of movement of the rods 25, thus obviating the cramping of the said rods, which would otherwise occur.
- 20 While I have shown in the drawings only one head 24, rod 25 and standard 26, it will be understood that the guide rail will be similarly supported at the opposite end.

In the foregoing, I have only described 25 so much of a routing machine and an ellipsograph attachment applied thereto as will give a clear understanding of the application of my invention. I will now proceed to describe my invention and its function in 30 connection with the above mentioned machines.

The body 30 of the locking device is provided with offset portions 31, which are arranged to engage the guide rail 23 and support the body in any desired position throughout the length of the rail. The body 30 is held against lateral movement by thumb screws 32 (in the present instance two are shown), which have a screw threaded engagement with the body and are arranged in position to engage plugs 33. These plugs are beveled at their lower ends, as shown at 34 in Fig. 6, and are moved in a vertical direction toward the lower edge of 40 the guide rail, through a hole 35 in the body, by the inward movement of the thumb screws 32, which have chamfered points 36 to coact with the beveled edges 34 of the plugs. The plugs are held with their beveled edges 34 in contact with the point 36 by means of pins 37 fixed in the body and entering slots 38 in the plugs. This pin and slot engagement also limits the upward and downward movement of each of the 45 plugs.

A vertical hub 39, having a socket therein, extends outwardly from the body 30 in position to receive a shank 40 depending from a rocking adjustment lever 41. The rocking 50 movement of this lever is controlled by means of thumb screws 42, 43, which have a screw threaded engagement with ears 44, 45, on the lever 41, the free ends of which screws are arranged to be screwed into and 55 out of contact with the body 30.

The rocking lever is also provided with an arm 46 which extends outwardly therefrom, and has a handle 47 for convenience in manipulation. A stud 48 is carried by the arm 46 and is fitted to receive a hub 49 having a horizontal lug 50, upon which is mounted a cradle 51 for the reception of the cutter supporting bar 3. The cradle is retained loosely upon the lug 50 by means of a collar 52, which prevents longitudinal movement 70 of the cradle on the lug. A binding screw 53 is located in the cradle in position to lock the bar 3 in place. The shank 40 of the rocking lever 41 may be rigidly fastened to the hub 39 by a horizontally sliding pin 54 80 which extends through the hub and projects a sufficient distance to receive a wing nut 55. The pin 54 is cut away at 56, as shown in dotted lines in Figs. 2 and 3, which cutaway portion engages the shank 40 and locks it 85 tightly in its socket when the wing nut bears against the hub 39.

In operation, assuming that the bed plate 1, the ellipsograph attachment, and the plate to be cut, are in position beneath the router cutter 5, and the ellipsograph attachment adjusted to cut a groove, such as that represented by 57 (Figs. 7 and 8); the cradle 51 is fitted to the arm 3 and the thumb screw 42 adjusted until it contacts with the 90 body 30, as shown in Fig. 3. While in this position, the parts are locked by actuating the wing nut 55 on the pin 54 and the binding screw 53, which latter secures the bar in the cradle. The screws 32 are also advanced 100 so as to lock the supporting device to the guide rail 23, as already described. With the several parts thus adjusted, and locked, the bar 3 may be lowered by actuating the parts 25, 27, 28, as already described until 105 the cutter 5 engages the work; whereupon the table 19 with the plate 20 thereon may be rotated by the handles 22. At the completion of this cutting operation, the guide rail may be raised thus withdrawing the 110 cutter from its work.

If it is now desired to cut a groove or a rabbet (e. g. 58, Figs. 7 and 8), parallel to the groove 57; the wing nut 55 and binding screw 53 may be loosened and the arm 47 115 swung until the cutter 5 is the desired distance away from the groove already cut. In this position, the screw 43 is advanced until it engages the body 30, and the wing nut and binding screw 53 again tightened. 120

The operation of the machine is now repeated and the cut 58 effected.

In order to cut identical lines or grooves on additional plates, the operation already described is repeated, viz; by first manipulating the handle 47 to rock the lever 41 so that the screw 42 contacts with the body 30, thus holding the bar 3 in position for the cutter to cut one line on the plate after which the lever 41 may be rocked so that the screw 130

43 engages the body in which position the bar is held so that the cutter may cut a second line. It will be understood that different widths of routing tools may be applied 5 other than the one shown.

In Figs. 7 and 8 I have shown a plate having a groove 57 routed with a cutter of small diameter and a rabbet 58 routed with a cutter of large diameter. This rabbet 58 10 forms an edge by which the plate 20 may be secured to a block 60 by nails 61. When the plate is printed, the groove 57 is reproduced as a white border line and the intervening strip 59 between the groove 57 and 15 the rabbet 58, as a black border line.

What I claim is:—

1. In a routing machine, the combination with a cutter supporting bar, a cutter carried thereby and a vertically movable guide 20 rail, of a device having a slidable engagement with said rail and adapted to be clamped thereto, and means coöperating with said device and arranged to engage said bar for freely moving it a limited distance 25 in the device to enable the cutter to operate in predetermined places on the work presented to it.

2. In a routing machine, the combination with a cutter supporting bar, a cutter carried thereby and a guide rail, of a removable 30 device comprising a body adapted to be clamped to said rail and means coöperating with said body for engaging said bar, said means being arranged to be moved a limited 35 distance on the body.

3. In a routing machine, the combination with a cutter supporting bar, a cutter carried thereby and a guide rail, of a removable 40 device comprising a body adapted to be clamped to said rail and oscillatable means coöperating with said body for engaging said bar, said means being arranged to be oscillated on the body.

4. In a routing machine, the combination 45 with a cutter supporting bar, a cutter carried thereby and a guide rail, of a removable device comprising a body adapted to be clamped to said rail, oscillatable means coöperating with said body for engaging 50 said bar and adjustable elements mounted on the body for limiting the movement of said oscillatable means.

5. In a routing machine, the combination with a cutter supporting bar, a cutter car-

ried thereby and a guide rail, of a removable 55 device comprising a body adapted to be clamped to said rail, an arm pivoted thereon and means on said arm for engaging said bar.

6. In a routing machine, the combination 60 with a cutter supporting bar, a cutter carried thereby and a guide rail, of a removable device comprising a body adapted to be clamped to said rail, an arm pivoted thereon, movable elements mounted on the body 65 for limiting the movement of said arm and means on the arm for engaging said bar.

7. In a routing machine, the combination 70 with a cutter supporting bar, a cutter carried thereby, and a guide rail, of a removable device for holding the bar to said rail in a position to be rocked, said device comprising a body adapted to be clamped to said rail, an arm pivoted thereon and provided with means adjustably mounted in 75 said arm and coacting with said body for limiting the movement of said arm, and means mounted on said arm for engaging said bar.

8. In a routing machine, the combination 80 with a cutter supporting bar, a cutter carried thereby, and a guide rail, of a removable device for locking the bar to said rail, said device comprising a body adapted to be clamped to said rail, an arm pivoted 85 thereon, means for locking said arm to the body, adjustable means coacting with the body for limiting the movement of said arm, means mounted on the arm for receiving said bar, and means for locking the bar 90 to said last-named means.

9. In a routing machine, the combination 95 with a cutter supporting bar, a cutter carried thereby, and a vertically movable guide rail, of a device adjustable on said rail for maintaining the bar in a position capable of a limited movement in various directions and with the cutter in predetermined position to be moved radially with respect to the work, and means for moving the rail 100 vertically to feed the cutter toward and away from the work.

In testimony, that I claim the foregoing as my invention, I have signed my name this twelfth day of December nineteen hundred 105 and sixteen.

VERNON ROYLE.
